UNITED STATES PATENT OFFICE.

LOUIS MARTIN, OF NEW YORK, N. Y.

SADDLE.

1,108,597.

Specification of Letters Patent. Patented Aug. 25, 1914.

Application filed December 23, 1913. Serial No. 808,446.

To all whom it may concern:

Be it known that I, LOUIS MARTIN, a citizen of the United States, residing at New York, in the county of New York and 5 State of New York, have invented certain new and useful Improvements in Saddles; and I do hereby declare the following to be a full, clear, and exact description of the invention, such as will enable others skilled 10 in the art to which it appertains to make and use the same.

This invention relates to new and useful improvements in saddles, which are particularly adapted to hold running boards to the 15 top of freight cars, and has for its object to provide a device which will hold the running boards more firmly in place than is done at present.

Another object of the invention is to provide a saddle to fit the top of the car which may be easily and quickly detached and replaced should it be desired to do so at any 20 time.

A further object of the invention is to 25 provide a device which will firmly hold the running boards in place and eliminate the use of screws, nails or other fastening means for the running boards.

A still further object of the invention is 30 to provide a device wherein the running boards may be easily and quickly detached from their position to permit the same to be repaired or replaced should it be so desired.

35 Another and further object of the invention is to provide a securing means for the running boards which will effectively hold the same to the car roof without the necessity of having any projecting parts over 40 which the brakeman in traveling across the car roof is apt to fall. Heretofore in the building of freight cars, the saddle for the roof has been constructed of wood or similar material and the running boards screwed 45 or nailed thereto and in the use of the car, the running boards have become loosened and projections left by the loosened portions of the running boards have endangered the lives of brakemen in traversing the top of 50 the car. This invention is principally to

eliminate the danger of injuring and such loss of life.

With the above and other objects in view, the invention consists in the combination and arrangement of parts which will be 55 fully set forth in the following specification and accompanying drawings, in which—

Figure 1 is a top plan view of a portion of a freight car showing the saddle and running boards in place, Fig. 2 is a side 60 view of one of the saddles showing the same partly in section to more clearly illustrate the construction thereof, Fig. 3 is a longitudinal sectional view of one of the saddles showing the same as it would appear when secured to a car, Fig. 4 is an end 65 view of the saddle showing the detailed construction thereof, and Fig. 5 is a transverse sectional view taken on line 5—5 of Fig. 3 showing the saddle removed from the car 70 roof.

Referring now to the drawings by characters of reference, the numeral 1 designates the roof of a railway car having the usual rib 2 extending transversely thereof. The 75 running boards, which are secured to the car roof are designated by the numerals 3, 4, and 5, and are held thereto by means of the saddle which is designated generally by the numeral 6. Each of the saddles 6 consists 80 of a pair of coöperative elements 7 and 8 which will be more fully hereinafter described.

Taking up the description of the elements separately, the numeral 7 designates as an 85 entirely the base portion of the saddle which is preferably of cast iron and comprises the substantially T-shaped member, the stem of which terminates in a substantially U-shaped member 10. The arm of the 90 U-shaped member terminates as shown in Figs. 2 and 5 in the flanges 11 which engage the top of the car immediately adjacent the rib 2. The U-shaped member is so constructed as to form the longitudinal trough 95 12 which straddles the rib upon which the device is secured as clearly illustrated in the drawings. This trough 12 is preferably angular in form as shown in Figs. 2 and 3 to conform to the pitch of the car roof. 100

The terminals of the elements 7 are provided with the web 13 having formed at their lateral extremities the beads 14 and 15, the space between said beads forming a 5 guide way for the reception of the arms of the U-shaped member 8 as clearly shown in Fig. 4. A pair of spacing blocks 16 and 17 are secured to the flat side of the elements 7 as clearly shown in Fig. 3 and are so arranged 10 as to hold the running boards 3, 4, and 5 in spaced relation. Centrally located of the element 7 is preferably provided the cylindrical enlargement 18 which is formed integral with the stem of the T-shaped member 15 as clearly shown in Fig. 2, and is provided with the longitudinally extending central aperture 19 through which the bolt 20 is adapted to extend to hold the saddle firmly in place on the roof of the car. At 20 each terminal of the stem of the T-shaped member is preferably provided the recess 21 which registers with the aperture 22 formed in the web portion 13, and coöperates with said aperture in retaining the bolt 23 in 25 place. Said recess is so constructed as to provide easy access to the aperture 22 to assist in the insertion of the bolt.

Having described the element 7, it now remains to fully set forth the construction 30 of the element 8 which is substantially in the form of a U-shaped member, the arms of which are provided at their terminals with the recesses 24, which conform to the shape of the trough 12, as clearly shown in Fig. 35 4, and are adapted to receive the rib 2 when the device is in position on the top of the car. A suitable aperture 25 is formed in each of the arms of the U-shaped member as clearly shown in Figs. 2 and 3 and are 40 adapted to register with the apertures 22 when the U-shaped member is in position on the coöperating element 7, as will be clearly seen upon referring to the drawings. It will be apparent that when the apertures are in 45 alinement, the bolt 23 may be inserted therethrough and the nut 26 screwed on the threaded end of the bolt and the coöperating element held firmly in place.

As clearly illustrated in Fig. 5, each of 50 the running boards may be provided with a transverse groove in which the bight portion of the U-shaped member 8 is adapted to rest, thus eliminating any projection extending beyond the upper surface of the running board.

It will be clearly seen from the foregoing, 55 that when it is desired to make use of this invention the element 7 is secured to the roof of the car by means of the bolt 20 and in such position that the arms of the U-shaped member 10 straddle one of the ribs of the car. The running boards are then placed in position as shown in Figs. 1 and 3 and the U-shaped element 8, which coöperates with

the element 7, is then placed over the running boards with the arms of said U-shaped member extending between the beads 14 and 15 formed on the web 13 of the element 7. It will be evident upon referring to the drawings, that when the U-shaped member 70 is down on the element 7 to its farthest extent, the apertures 22 and 25 will come into alinement and the bolt 23 may be passed therethrough. The nut 26 is then placed on the bolt, and it will be apparent that the running board will be firmly held in place and as there are no screws or nails in the ends of the running boards to hold the same in position, much of the danger in traversing the top of cars is eliminated.

While in the foregoing there has been shown and described the preferred embodiment of this invention, it is to be understood that such changes in the combination and arrangement of parts may be made 85 which may fall within the scope of the claims hereunto appended.

Having thus described my invention, I claim:

1. In a device of the character described, 90 the combination with a body portion being substantially T-shaped in cross section, a U-shaped member formed integral with the stem of the T-shaped member, said U-shaped member forming a longitudinal trough, webs formed at the ends of the body portion, said webs connecting the U-shaped member with the arms of the T-shaped member, of a coöperating element comprising a U-shaped member, the ends of the U-shaped member being provided with recesses conforming to 95 the shape of the first mentioned U-shaped member, means to hold the second mentioned U-shaped member in place on the body portion, and means to secure the body portion 100 to the top of a railway car.

2. In a device of the character described, 110 the combination with a railway car having a ribbed roof, of a body portion adapted to be secured to the roof of the car, said body portion comprising a T-shaped member and a U-shaped member formed at the end of the stem of the T-shaped member and extending throughout its entire length, said U-shaped member being adapted to straddle 115 the ribs on the top of the car, guide ways formed integral at the ends of the body portion, and a second U-shaped member adapted to coöperate with the body portion, the arms of said U-shaped member being 120 adapted to extend into the guide ways formed on the body portion, and means to secure the second mentioned U-shaped member to the body portion.

3. In a device of the character described 125 the combination with a railway car, of a body portion adapted to be secured to the roof of the car and conform to the shape

thereof, guide ways formed at the ends of the body portion, a plurality of bearing portions formed at the top of the body portion and adapted to receive running boards, and a U-shaped member coöperating with the body portion and adapted to overlie the whole, said U-shaped member having the ends of the arms to straddle the ribs on the roof of a railway car, and means to hold the

U-shaped member in place on the body portion. 10

In testimony whereof I affix my signature in presence of two witnesses.

LOUIS MARTIN.
